SAFE LOCK

George A. Cardell, New Britain, Conn.

Application August 28, 1945, Serial No. 613,135

5 Claims. (Cl. 109—59)

1

This invention relates to locks for safes and the like and more particularly to means for rendering relatively tamper-proof a lock of the combination type wherein locking dogs are used to secure the door of the safe against opening.

An aim of the invention is to provide in a safe lock of this type a device of simple construction and inexpensive to manufacture which will substantially reduce the possibility that unauthorized persons can open the safe by "feeling" the combination thereof.

A further aim of the invention is to provide, in a safe of the type wherein locking dogs are used to secure the door, a device on the dogs which will prevent a tamperer from discovering the safe-opening positions of the dogs.

A further aim of the invention is to manufacture the dogs employed in a safe lock in such form and configuration as to make it relatively impossible to open the safe without prior knowledge of the combination.

Other objects will be in part obvious and in part pointed out more in detail hereinafter.

The invention accordingly consists in the features of construction, combination of elements and arrangement of parts which will be exemplified in the construction hereafter set forth and the scope of the application of which will be indicated in the appended claims.

In the drawings:

Figure 1 is a longitudinal side view in partial section of a safe in which is incorporated the present invention, the safe being shown as set in a concrete structure;

Fig. 2 is an elevational view of the front of the safe;

Fig. 3 is a perspective view of the dial key, and

Fig. 4 is a perspective view of one of the locking dogs.

Referring now to the present illustrative drawings, there is shown a safe embedded in the concrete structure *g* of a building. The safe has a casing, cylindrical in shape and comprising two firmly united sections, the vault section *h* and, forward of it, the door-containing section *f*. The casing is suitably flanged, as at 10, 11 and 12, so that it will be difficult to remove the safe from the structure by chipping away the surrounding concrete. The forward door-containing section *f* of the casing has a bore 15 which is increased in diameter at its inner end to provide an annular shoulder 16. Adjacent its outer end, the casing is counterbored to form a shoulder 17 and the counterbore is flared, as at 18, to provide a space for gripping the door 20 to withdraw it. The door 20 is cylindrical and slidably fits in the bore 15. A hardened drill-proof metal plate 21 is secured to the inner end of the door by a bolt 22. The rear surface of plate 21 is in substantial alignment with the shoulder 16 and a shoulder 17 on the door adja-

2

cent its outer end rests against the shoulder 17 of bore 15 when the door is fully inserted into the bore.

Angularly spaced apart adjacent the periphery of the door and extending longitudinally therethrough are holes 23 (six holes being shown in the present illustrative drawings), and rotatably mounted in these holes are hardened-metal lock shafts 25 which are reduced in diameter, as at 27, to provide shoulders 27'. The reduced portions 27 of the lock shafts 25 project through plate 21 and the shoulders 27' rest against the plate. Rigidly secured to the inner ends of the shafts are locking dogs 30. The outer ends of the shafts 15 are provided with steps 26 which are set back a substantial distance from the front face of the door in order to render it difficult to turn the shafts except with the dial key *d* (Fig. 3). This key has a cylindrical head 28 which is numbered on the perimeter thereof and secured to the head is a stem 29 adapted to fit into holes 23. Stem 29 has a step 26' at its end which interfits with steps 26 of lock shafts 25 so that, when the stem of the dial key is inserted in one of the holes 23, the step 26' will cooperate with the step 26, and the lock shaft can be rotated by turning the key. On the outer perimeter of the door, adjacent the holes 23, are provided marks 36 which act as guides for setting dial key *d* at the proper position for opening the door.

The dogs 30 are constructed in a generally round shape and extend laterally behind the step 16. On each dog is provided a surface 31 which is alignable with the bore 15. When the shafts 35 have been adjusted so that surfaces 31 are in alignment with bore 15, the door can be removed from the casing. The safe is locked by inserting the door into the bore and turning surfaces 31 out of alignment with bore 15. In the absence 40 of my invention, the ends 32 of the dogs engage against shoulder 16 and prevent the removal of the door. To open the safe, it would, therefore, appear necessary to know, for each separate lock shaft, the proper setting of the dial key with respect to the mark 36. However, in order to be slidably movable in bore 15, the door 20 must be slightly smaller in diameter than the bore. This permits a slight tilting or canting of the door even when it is locked securely. Tamperers or safe breakers can determine the position of the dogs 30 by pulling out and canting the door and "feeling" the contact of the edges of the surfaces 32 of the dogs against the shoulder 16. By "feeling" 45 the contact of each dog against the shoulder and adjusting the lock shaft, the surfaces 31 of the dogs can be aligned with the bore 15 since, when they are so aligned, the door can be canted further before any positive contact is felt (the contact will then be that between the edge of shoulder 16 and surface 32). Unauthorized persons could thus determine the door-opening position

of each individual dog and open the safe without prior knowledge of the combination.

In accordance with the present invention, in order to prevent the opening of the safe by this method, dogs 30 are provided, at their outer ends, with polygonal-shaped portions 33 (shown in the present illustrative drawings as being of a hexagonal shape). Each edge of a polygonal-shaped portion 33 is adapted to align with bore 15 but only one edge 34 is coextensive with surface 31 of the dog. Portion 33 is of sufficient thickness so that even when an edge is aligned with bore 15 and the door canted as far as possible, the perimeter of the polygonal portion and not the surface 32 of the dog will engage the edge of shoulder 16. As a result, it is impossible to "feel" the combination as hereinabove described. Since all aligned positions feel alike, there is only one chance in six (where hexagonal portions are used) that, having aligned one edge of a portion 33 with the bore 15, the tamperer will have discovered the proper edge 34 which is coextensive with surface 31 of the dog.

It will be seen from the description that the present invention represents a distinct advancement in rendering a safe tamper-proof. My arrangement thwarts persons attempting to "feel" the combination, because the polygonal-shaped portion intervenes between the main locking dog and the inner shoulder and provides, in effect, a plurality of false combinations, all of which "feel" the same as the true combination, thus making it impossible for the tamperer to open the safe by anything other than guess work. The chances that an unauthorized person could open a safe incorporating the present invention are negligible. In the present instance, six-sided portions are provided on the dogs and there are six dogs; thus, the chance of discovering the right combination is only one in 46,656 (or 6⁶). This ratio can be further reduced by increasing the number of edges on the polygonal-shaped portion and the number of shafts and locking dogs employed. The number shown in the present illustrative drawings have been found to be adequate to thoroughly protect the safe against tampering individuals. It will also be seen that the present invention does not interfere with or make more difficult the opening of a safe when the proper combination is known.

As many changes could be made in the above construction and many apparently widely different embodiment of this invention could be made without departing from the scope thereof, it is intended that all matter contained in the above description or shown in the accompanying drawings shall be interpreted as illustrative and not in a limiting sense.

It is also to be understood that the language used in the following claims is intended to cover all of the generic and specific features of the invention herein described and all statements of the scope of the invention which, as a matter of language, might be said to fall therebetween.

I claim as my invention:

1. In a safe, a casing having a bore, a shoulder at the inner end of said bore; a door slidably fitting in said bore; a rotatable lock shaft longitudinally disposed in said door, extending inwardly therefrom and secured thereto against longitudinal displacement; a locking dog fixed to the inner end of said shaft and projecting laterally behind said shoulder; a surface on said dog alignable with said bore; and a raised portion on said dog extending from the outer end thereof.

2. In a safe, a casing having a bore, an annular shoulder at the inner end of said bore, a door slidably fitting in said bore; a rotatable lock shaft longitudinally disposed in said door, extending inwardly therefrom and secured thereto against longitudinal displacement; a locking dog fixed on the inner end of said shaft and projecting laterally behind said shoulder, said dog having a surface on the periphery thereof alignable with said bore; and a portion on the outer end of said dog extending behind said shoulder having a plurality of edges alignable with said bore, one of said edges being coextensive with said surface.

3. In a wall safe, a casing having a longitudinal bore, an annular shoulder at the inner end of said bore; a door slidably fitting in said bore and removable therefrom; a plurality of rotatable lock shafts longitudinally disposed in said door, extending inwardly therefrom and secured against longitudinal displacement; means for rotating said lock shafts from the outer end of said door; locking dogs fixed on the inner ends of said shafts and projecting laterally behind said shoulder, surfaces on the periphery of said dogs alignable with said bore; and polygonal-shaped portions on the outer ends of said dogs having a plurality of edges alignable with said bore, one of said edges being coextensive with the said surfaces on said dogs.

4. In a safe, a peripherally flanged casing having a bore, a shoulder at the inner end of said bore, a door slidably fitting in said bore and removable therefrom, said door having a plurality of longitudinal holes therethrough; a plurality of rotatable lock shafts in said holes, secured therein against longitudinal displacement and extending inwardly from said door; locking dogs fixed to the inner ends of said shafts and projecting laterally behind said shoulder, each dog having a surface on the periphery thereof alignable with said bore; and raised portions on the outer ends of said dogs extending laterally behind said shoulder and having a plurality of edges on the periphery thereof alignable with said bore, one of said edges being coextensive with said surface.

5. In a safe of the character described, a casing having a plurality of peripheral flanges, said casing also having a bore, an annular shoulder adjacent the inner end of said bore; a door slidably fitting in said bore and having a plurality of longitudinal holes therethrough; rotatable lock shafts in said holes, extending inwardly therefrom and secured against longitudinal displacement, the outer ends of said shafts being positioned inwardly from the outer face of said door; means including a stem insertable into said holes and engageable with said shafts for rotating said shafts from the outer face of said door, locking dogs fixed to the inner ends of said shafts and projecting laterally behind said shoulder, and a surface on the periphery of each of said dogs alignable with said bore.
